UNITED STATES PATENT OFFICE.

HARRY A. CUMFER, OF CHICAGO, ILLINOIS, ASSIGNOR OF ONE-HALF TO ALBERT D. STEWART, OF HUTCHINSON, KANSAS.

PLASTER-RECEIVING BOARD.

Application filed January 23, 1922. Serial No. 531,037.

To all whom it may concern:

Be it known that I, HARRY A. CUMFER, a citizen of the United States, residing at Chicago, in the county of Cook and State 5 of Illinois, have invented certain new and useful Improvements in Plaster-Receiving Boards, of which the following is a specification.

This invention relates to plaster-receiving 10 boards.

One of the objects of the invention is to provide an inexpensive, strong, durable, and serviceable plaster-receiving board.

Another object is to provide a plaster- 15 receiving board by making it of a single imperforate sheet of water and moisture resistant material.

Another object is to make a plaster-receiving board by forming a series of parallel 20 ribs of a single sheet and cementing parts of the sheet together in fashioning the ribs, and providing in the ribs means for keying the plaster to the board.

Other objects and advantages will here- 25 inafter appear to persons skilled in the art from a consideration of the following description when taken in conjunction with the drawings, wherein:

Fig. 1 is a plan view of the plastered 30 wall with parts broken away showing part of the plaster-receiving board thereunder.

Fig. 2 is an enlarged section taken on line 2—2 of Fig. 1.

Fig. 3 is a view similar to Fig. 1, of a 35 modified form of board.

Fig. 4 is an enlarged section taken on line 4—4 of Fig. 3.

In all the views the same reference characters are employed to indicate similar parts.

The plaster-receiving board is made of a 40 single sheet 5, preferably of waterproof and moisture-proof material such, for example, as a fibrous sheet saturated with hot asphalt and preferably coated with the same.

45 material of a somewhat different consistency which will serve as a cement when heated and cooled, and which is not soluble in water. The sheet is bent to form the ribs 6 in which the parallel sides 7 and 8

50 are cemented together at 9 by application of pressure to the two sides while the asphalt is hot, and the upper portion 10 of the rib is mashed down upon the outstanding parallel surfaces 11 and 12 of the

ribs and cemented to the same by the hot 55 asphalt 13 and by application of pressure to the parts. When the cementitious material has cooled the parts will adhere firmly together and the cement is not soluble in water and therefore any dampness that 60 may penetrate to the joints between the parts 7 and 8 will not cause them to spread apart. The ribs 10 are parallel and the overlying heads form means for keying the plaster between adjacent ribs, as clearly 65 shown in Figs. 1 and 2. The part 14, between adjacent ribs, is sufficiently flexible to permit the structure to be rolled upon a reel in which compacted condition it may be advantageously stored or prepared for 70 shipment.

In the modifications shown in Figs. 3 and 4 the head 10 of the ribs 6 is left off and holes 16 and 17 are made thru the parts 7 and 8, thru which the plaster will key. 75 In neither case are the ribs 6 or 10' of height sufficient to extend entirely thru to plaster 18, when the same is applied to the plaster-receiving board. When applying 80 the plaster-receiving board to a supporting structure, nails are passed thru the parts 14 that are located between the ribs.

When the plaster receiving board is applied to a studded wall, the ribs 6 and 10' are preferably placed at right angles to the 85 longest axis of the studs, so that the ribs will stiffen the structure when supported by the studs.

The cementing effect produced by the hot asphalt will sufficiently hold the parts 7 90 and 8 together and after the nails have been placed thru the parts 14 the cement is thus relieved, in a large measure, of stress by the supporting effect of the nails.

The sheet 5 is imperforate and water-resistant and therefore moisture, wind or water cannot pass thru the plastered wall and appear inside on the plastered surface. The sheet is also a poor conductor 100 of heat and therefore there will be very little, if any, condensation of moisture on the inner surface of the plastered wall as a result of frost penetration.

Having described my invention what I claim as new and desire to secure by Letters Patent, is:—

1. A plaster-receiving board comprising a single sheet uniformly coated throughout

with an adhesive plastic material and crimped to form a series of parallel, laterally extending, integral, plaster-keying ribs, the sides of the ribs cemented together by 5 the contacting coating.

2. A plaster-receiving board comprising a single sheet uniformly coated throughout with an adhesive plastic material and crimped to form a series of parallel, laterally extending, headed ribs, the sides of the 10 ribs cemented together and the parts of the

heads cemented together by the contacting coating.

3. A plaster-receiving board comprising a single elongated sheet, cement-coated 15 throughout and crimped to form a series of transversely extending, outstanding ribs, the parts of the ribs cemented together by the normal coating.

In testimony whereof I hereunto sub- 20 scribed my name.

HARRY A. CUMFER.
